UNITED STATES PATENT OFFICE.

CHARLES GORDON MACGREGOR, OF BUFFALO, NEW YORK, ASSIGNOR TO CURTISS AEROPLANE AND MOTOR CORPORATION, A CORPORATION OF NEW YORK.

FLYING-BOAT HULL.

1,316,908.

Specification of Letters Patent. Patented Sept. 23, 1919.

Application filed September 14, 1917. Serial No. 191,470.

To all whom it may concern:

Be it known that I, CHARLES G. MACGREGOR, a citizen of the United States, residing at Buffalo, in the county of Erie and 5 State of New York, have invented certain new and useful Improvements in Flying-Boat Hulls, of which the following is a specification.

My invention relates to hydroplane boats 10 of the type commonly used in connection with hydroaeroplanes and flying boats. It is characterized principally by a continuation or prolongation of the fin excrescencies (which distinguish Curtiss flying boats) 15 rearwardly beyond the line of demarcation between the fore body of the hull and the tail. This line of demarcation is usually indicated by a transverse break in the longitudinal continuity of the hull bottom com- 20 monly called a step. (If a plural or multiple number of steps are provided that portion of the hull aft of its lowermost point may be said to constitute the tail).

By extending the fin excrescencies rear- 25 wardly beyond the step, it is proposed to materially increase and at the same time longitudinally distribute the buoyancy in such manner that the center of buoyancy lies more nearly amidships with the result 30 that the craft is floated higher in the water. The seaworthiness of the hull is also im- proved and the trim materially bettered. In the manufacture of finned boat hulls as at present constructed, difficulty is ex- 35 perienced in construction work by reason of the abrupt termination of the hydroplane bot- tom of the boat in transverse alinement with the step. Such construction necessitates a discontinuance of the fin edge stringers and 40 other hull parts at the very point where the greatest strength is needed. A continuation of these essential parts beyond the step without interrupting the continuity of the bottom foundation increases greatly the 45 strength of the hull both longitudinally and transversely and at the same time simplifies construction to a very considerable extent. Moreover, the extended fins tend to resist 50 rolling action. In addition a plural num- ber of steps may be provided in the hull bottom with a minimum of structural changes. Better streamlines are also pro- 55 duced.

In the drawings, wherein like characters

of reference designate like or correspond- 55 ing parts;

Figure 1 is a plan view of a flying boat hull equipped with fins constructed to bridge the step;

Fig. 2 is a side elevation of the hull as 60 illustrated in Fig. 1, and

Figs. 3, 4, and 5 are sections respectively on the lines 3—3, 4—4, and 5—5 of Fig. 2.

The fore body of the hull I have design- 65 ated in its entirety as 10. It is provided 70 with a hydroplaning bottom 11 of V-form in transverse section and with a relatively blunt nose 12. The tail 13 of the hull is in reality an integral part of the fore body 10 being merely a continuation thereof rear- 75 wardly as shown. The bottom 14 of the tail portion of the hull may be said to ex- 80 tend rearwardly and slightly upwardly from its point of inception at the step 15. This step affords a line of demarcation be- 85 tween the fore body 10 and tail 13 and in flying boats approximately underlies the center of gravity of the machine. Ordin- 90 aily but one step is provided. Two or more steps, however, may be equally as well used. The function of the step or steps is to de- 95 crease suction and skin friction while hydroplaning and to permit of the proper distribution of more or less air beneath the hull.

Fin excrescencies 16 are provided at op- 95 posite sides of the hull to augment the hydroplaning bottom 11 and add buoyancy to the craft. These fins in machines of this type heretofore constructed have terminated 100 rearwardly squarely in alinement with the step 15. In none of these machines have the fins been continued beyond the step. A continuation of the fins 16 beyond the step adds greatly to the seaworthiness and struc- 105 tural strength of the hull without increasing either the skin friction while hydro- planing or the head resistance while in the air. The fins 16 as shown, emanate from a point in the vicinity of the bow end of 110 the hull and gradually widen out to a point of maximum width in the vicinity of the step. From said point aft the width of the fins decreases gradually; the fins at their rear extremities merging into the sides of 115 the hull at a point considerably aft of the step, preferably approximately three-fifths astern of the full length of the hull. The

fins may be thus described as bridging the step. Their transverse and longitudinal section is such that even better streamlines are produced than heretofore. This is possible because of their horizontal flatness, as it were, rather than their inclination toward the step from the bow as heretofore. Where more than one step is provided the fins should continue rearwardly from their 10 points of inception beyond at least one of the steps and where more than one step lies in advance of the rearward termination of the hydroplaning bottom, the fins should bridge said point. The fins thus extended 15 afford a good protection for the main hull and insure the safety of the boat against sinking when divided longitudinally into water-tight compartments should one or both fins be fractured or from other cause 20 spring a leak. Still another advantage obtained through such a fin construction is the better foundation afforded for the effective bracing of the conventional stub wings found in most Curtiss flying boats. Obviously, 25 a brace might be extended diagonally inwardly from the rear wing beam of the stub wing to the fin at each side of the hull in much the same manner as the brace arrangement which at present characterizes the forward wing beam. The principal advantages, however, are as heretofore pointed out, *i. e.*, the added buoyancy; the uniform longitudinal buoyancy distribution, the simplified construction and the 30 bringing of the center of buoyancy more nearly amidships.

The fin excrescencies although disclosed as of decreasing width both fore and aft from a point in transverse alinement with the step 40 may obviously be made or constructed in various forms. Also, they may be continued

rearwardly to a point adjacent the stern post of the hull or continued only slightly rearwardly beyond the step. What I emphasize is the continuation of the fins rearwardly beyond the step or rather beyond that point in the hull bottom rearwardly terminating its hydroplaning surface. 45

What is claimed is:

1. In a hull for flying boats, a bottom 50 surface having its longitudinal continuity interrupted transversely by a rearwardly facing step, and fin excrescencies formed in lateral continuation of said bottom surface both in advance of and aft of said step. 55
2. In a hull for flying boats, a fore body having a bottom surface of hydroplaning form, a tail portion and fin excrescencies formed in lateral continuation of the bottom of the tail portion, said fins being longitudinally continuous from a point in the vicinity of the bow end of the fore body to a point intermediate the extremities of the tail. 60
3. In a hull for flying boats, a bottom 65 surface having its longitudinal continuity interrupted transversely by a rearwardly facing step, and longitudinally streamlined fin excrescencies formed in lateral continuation of said bottom both in advance of and 70 aft of said step.
4. In a hull for flying boats, a bottom surface having its longitudinal continuity transversely interrupted by a rearwardly facing step, and lateral fin excrescencies arranged to augment said bottom surface, the width of said excrescencies decreasing gradually both fore and aft from a point adjacent said step. 75

In testimony whereof I hereunto affix my 80 signature.

CHARLES GORDON MACREGOR.
